APPARATUS FOR POLISHING PLATE GLASS

Application filed July 27, 1923. Serial No. 654,093.

This invention relates to improvements in the art of making polished plate glass, and more particularly to a new and improved apparatus for polishing the surfaces of flat-ground sheets of glass.

It has among its objects to finish flat-ground plates of glass in an expeditious and economical manner, and to eliminate or simplify various steps in the polishing operation.

10 In the manufacture of plate glass, it is the practically universal practice to cement a number of the raw sheets or blanks to the surface of a large rotating table by means of plaster of Paris, and to then apply grinding and polishing tools in succession to the exposed faces of the fixed sheets. After one side of the sheets has been finished in this manner, they are pried loose, turned over, and again cemented down, after which the 20 grinding and polishing operation is repeated. Each sheet is first embedded in the plaster of Paris which not only cements the sheet to the table but fills up the spaces between sheets so that a continuous surface of glass and 25 plaster is exposed to the grinding tool. This sheet-holding table is then moved to position beneath a series of grinding tools or heads and the table and heads rotated about different centers so that the abrading action of 30 the grinders first reduces all of the sheets and plaster to a common level and then grinds the sheets until every sheet has a flat smooth surface suitable for polishing. The table is then removed from beneath the grinding 35 tools, the exposed faces of the sheets and plaster carefully cleaned, and such portions of the plaster bed as are loose or have been broken away are replaced. The table is now shifted into position beneath a series of 40 polishing heads where the surfacing process is completed. The table is then removed and the plaster broken away and the sheets pried loose. The sheets and table top are thoroughly washed, after which the sheets are 45 reversed to expose the unground surfaces and again plastered to the table. The grinding and polishing process is then repeated on the faces now uppermost, after which the sheets must again be broken away from the plaster 50 and then cleaned.

Serious objections to this practice have long been recognized and will be later apparent. The bond afforded by the plaster of Paris is not always sufficient, in which case the loosened sheets are thrown off by centrifugal force with serious loss by breakage. The cementing down of the sheets requires a very considerable amount of hard labor, as well as expensive material. This process known as laying or seating the sheet, must be very carefully and skillfully done or the sheets will become tilted out of the horizontal and the edges of some of the sheets will project above the common level. After laying a thin covering or blanket of wet plaster on the table top 55 the sheet is quickly laid on this plaster, after which several workmen stand on the sheet and work the sheet backwards and forwards with their feet until it has become seated as closely and rigidly as possible in the plaster. 60 No matter how skillfully this work is done it is almost impossible to seat the sheets with their upper surfaces absolutely horizontal, and the initial engagement of the grinding or polishing tools with the more exposed edges of the 65 sheets is responsible for much breakage. Also this tilting tends to produce sheets of unequal thickness by grinding off more glass in one part of the sheet than in another. Furthermore, even if none of the sheets is tilted, the 70 plaster of Paris layer may be thinner beneath one sheet than another, thus producing sheets of different thickness, although simultaneously surfaced. Also some of the raw sheets will inevitably be thicker so that grinding 75 must be continued to an extent sufficient to grind the thinnest or lowest sheet on the table. This use of cement to stick down the sheets also necessitates a cleaning operation to remove the plaster of Paris film which remains 80 to a certain extent on the original polished surface of the sheet after it has been finished and pried loose for the second time. The entire method is quite tedious and expensive, 85 and offers many opportunities for breakage. 90

Other means for holding the sheets upon the supporting table have been proposed, but the method described in detail above is the one now in practically universal commercial use.

The present invention relates to a radically different system of surfacing the sheets, which is faster, more economical and produces a more uniform finished article. The system is most advantageously employed for surfacing sheets of standard size and shape, preferably square. All of the edges of these sheets or blanks are slightly beveled to avoid chipping or fracturing of the sheet during the surfacing operation. Preferably, each individual grinding or polishing machine is adapted to work upon a single size sheet, and upon one sheet at a time, although a machine may be adapted for surfacing sheets of various sizes, or for surfacing more than one sheet at a time. The sheet or blank is not secured to the supporting table by plaster, but is merely placed loosely in a shallow recess in the table top, this recess preferably conforming to but being slightly larger than the glass sheet. The surfacing tool is then lowered so that its weight rests upon the glass sheet, and the weight of this tool in addition to the twisting movement which is imparted to the sheet when the rotation is commenced, serves to set the sheet firmly in the recess. When the exposed surface of the sheet is properly ground, the sheet is taken out, reversed, and the other side ground in a similar manner. This sheet now completely ground on both sides, is transferred to a quite similar polishing machine, where the surfacing operation is completed. This polishing machine comprises the subject-matter more specifically disclosed and claimed in this present application.

In the accompanying drawings:

Fig. 1 is a central vertical section through a portion of one of the polishing units.

Fig. 2 is a plan view of the sheet-supporting table, on a somewhat smaller scale.

Fig. 3 is a vertical section through a portion of the table on an enlarged scale, taken substantially on the line 3—3 of Fig. 2.

Fig. 4 is a view similar to Fig. 3, showing a different form of adjustment for the tool-supporting portions of the table.

The sheet-supporting table 1 is mounted at the upper end of column 2 which turns in bearings 3 in the frame-work 4. The table is preferably supported on suitable roller bearings 5 and is positively rotated by means of a large bevel gear 6 secured to column 2 and driven through bevel pinion 7 on a drive shaft 8, rotated from any suitable source of power, such as an electric motor. The table is round, but carries upon its upper face a flat square sheet-supporting member 9, whose center, in the construction here shown, substantially coincides with the center of the table. This member need not necessarily be square, but should substantially conform to the contour of the sheet to be surfaced on this machine. This supporting member 9 is preferably constructed of heavy metal so as to be

absolutely rigid, and its upper surface is ground as closely as possible to an absolute plane so as to serve as a "master" surface or pattern upon which the flat ground glass sheet is firmly and evenly supported. Surrounding this square supporting member is a series of four sectors 10, also secured to the top of table 1, which project somewhat higher than the upper surface of member 9 so that a square sheet-receiving recess or depression is provided in the top of the table. A sheet-supporting pad of yielding material 11 covers the upper face of member 9. The material best adapted for this purpose is cork, or a cork carpet formed of a very compact composition of ground cork and a linseed-oil gum has been found most satisfactory. This material, although sufficiently yielding, is waterproof, will not warp or swell, and will not absorb the rouge, used during the polishing operation, as will paper or cloth fabrics. Neither is it affected by the rather intense heat developed during the polishing operation. This cork composition also has a high coefficient of friction with the glass surface. This pad should be of absolutely even thickness, so that the master surface on supporting member 9 will be repeated on the upper surface of the cork pad. The walls of the square recess are outlined by vertical strips 12 of yieldable material such as rubber. The recess, the bottom of which is the pad 11 and the walls of which are determined by the yieldable strips 12, conforms to but is slightly larger than, the ground glass blank 13 which is to be polished. The upper surfaces of side sectors 10 project above the cork pad 11 a distance just equal to the thickness of the ground glass blank 13, so that the recess thus formed in the table top will have substantially the same dimensions as the glass blank.

The polishing tools are of standard design, each polisher comprising a felt pad 14 secured to the lower face of a weighted block 15 mounted freely by universal joint 16 at the lower end of a pivot pin 17. This pivot pin 17 is freely slidable vertically in one arm of a spider 18, freely pivoted at 19 in the supporting structure of the machine. Mechanism (not shown) is provided to lift the spider and polishing tools from the table and glass sheet when the polishing operation is completed, and lower the tools onto the sheet when a new polishing operation is to be performed. When in operative position the polishing tools rest with their entire weight upon the upper surfaces of the glass sheet and the side portions of the supporting table, and are permitted free movements in the orbit determined by the centrally pivoted spider 18. The polishing tools are not driven other than by the frictional resistance offered by the rotating table and sheet upon which they rest.

As here shown, three series of these polish-

ing heads are used. One larger series is so pivoted that the orbit of travel of the polishers will cover the center of the sheet as well as the edge portions thereof. Two other series of smaller polishers 20 are so mounted that their orbits of travel pass completely off from and on to the edge portions of the sheet, as shown more clearly in Fig. 2.

It is essential that these polishing pads be supported while off from the glass sheet, and that they be guided evenly onto and off from the sheet when in the outer portions of their orbits. To accomplish this, the upper faces of side sectors 10 of the table are formed of smooth metal plates 21. Preferably a hard metallic alloy, such as nichrome, capable of receiving and retaining a highly polished surface is used. These plates 21 are so mounted that their upper surfaces lie in the same horizontal plane as the exposed upper face of the ground glass blank 13, when placed within the sheet-supporting recess.

Since the ground glass blanks to be polished on one of these machines will ordinarily be of a uniform standard thickness, the plates 21 may ordinarily be designed of a proper thickness, and fastened permanently in place on the side sectors 10. However, to adapt these machines for polishing different thicknesses of plate glass, any suitable means for vertically adjusting the polished side plates 21 may be adopted, examples of which are shown in Figs. 3 and 4.

In Fig. 3, each plate 21 is provided with a series of dowels 22 fitting recesses 23 in the sectors 10. One or more suitably perforated thin shims 24 may be inserted between the polishing plate 21 and the supporting sector 10, after which the plate and shims are secured in position by screw-bolts 25. By varying the number of shims 24 used, the plane of the upper tool-supporting surface of plates 21 may be made to conform exactly with the tool-supporting surface of the glass blank 13 which is to be polished. Of course, the adjustment mentioned above need only be made at such times as the standard thickness of glass plates to be polished is changed.

A different form of adjustment is shown in Fig. 4. In this case the plates 21 are guided as before by dowels 22 operating in recesses in the supporting sectors 10. A plurality of threaded supporting bolts 26 extend downwardly from plate 21 through suitable apertures in the sector 10 and table 1, and each is in threaded engagement with a worm-wheel 27, rotated by worm 28 on a rotatable adjusting shaft 29. By suitably rotating shaft 29, the bolts 26 and consequently the plates 21 supported thereon may be vertically adjusted to any desired position. In this latter construction the yieldable edge members 12 which outline the recess in the table may, if desired, be secured to the plates 21 so that they may be vertically adjusted

along with the polished plates. The two adjusting means shown in Figs. 3 and 4 are merely examples of many different ways in which these tool-supporting plates 21 may be vertically adjusted to conform to the thickness of the glass plate to be polished.

In operation, when the machine is stationary, and the polishing heads 14 and 20 are all raised above the table, a flat ground sheet or blank 13, the edges of which have been slightly beveled, will be laid loosely directly upon the pad 11 in the table recess. When the polishing tools are lowered onto the sheet and the table 1 is rotated, the slight shifting movement allowed the sheet in the slightly oversize recess will permit the sheet to seat itself firmly and evenly upon the master supporting surface under the weight of the polishing tools. Usually, the sheet will slightly shift within the recess and wedge itself adjacent its corners against the yieldable side strips or abutments 12, as indicated in dotted lines in Fig. 2. With the square recess arranged substantially symmetrical over the axis of the table as here shown, there is very little tendency for the sheet to be thrown from the table when rotating, since the center of gravity of the sheet will lie substantially in the axis of rotation of the table. The frictional contact of sheet 13 with supporting pad 11, in combination with the wedging action of the sheets against portions of the yielding side walls or abutments 12, is sufficient to hold the sheet firmly against lateral shifting movement after the polishing operation is once under way. The sheet is held down against the master supporting surface by the weight of the polishing tools, aided to some extent by the binding action of the edge strips 12.

As is usual with machines of this general type, a mixture of rouge and water is fed to the contacting surfaces of the pads 14 and the glass blank during the polishing operation.

Since the smaller polishing pads 20 pass completely off the glass sheet while in the outer portion of their orbits, it is essential that they be supported during this portion of their travel, otherwise they would drop below the edges of the sheet and breakage would occur when they attempted to pass back onto the sheet. Furthermore, in order to secure a proper uniform polish on the edge portions of the sheet, it is essential that the upper supporting surfaces of members 21 practically coincide with the supporting surface of the glass sheet, as outlined in the previous description. Furthermore, if there is any direct engagement between the edges of the glass blank 13 and the felt polishing pads as the pads pass onto the sheet, the caked rouge on these pads, which is essential to the polishing operation, will be scraped away, and the pads will also be quickly cut to pieces by the sharp edges of the sheet.

With the edge-supporting plates 21 arranged as above described, no such engagement takes place, and the polishing tools are guided evenly onto and off from the sheet without injury to either the pads or the glass sheet being operated upon.

When one face of the sheet 13 is properly polished, the polishing tools are raised, the sheet is removed from the recess, turned over, and relaid in the recess with the unpolished surface uppermost, after which the polishing operation is repeated as above. Hand-holes 30 are preferably provided to facilitate lifting the glass sheet from the recess.

A plurality of individual separate recesses similar to the one here disclosed, might be arranged upon the single table top, to simultaneously polish several smaller sheets instead of one large one. However, the form here shown is preferable. Since a factory installation includes a large number of these machines, different groups of machines may be provided for different sizes of glass sheets.

The grinding operations which precede the polishing operations above described, are preferably performed upon a machine similar in many respects to the one here disclosed. This machine is described in detail and claimed in my copending application, filed of even date herewith. The broader claims to the new apparatus for holding the sheets during the surface process without the use of plaster of Paris or other cement, are contained in this companion application, the claims in the present case being limited to those features peculiar to the polishing machine.

However, this polishing machine is not limited to use with ground glass blanks produced on the grinding machine noted above. Any flat-ground glass blanks however produced, whose plane surfaces are parallel may be polished on this machine.

It is to be understood that in common practice, the machines employed will embody many auxiliary features not disclosed in this application, for example, means are provided to automatically raise and lower the grinding head when sheets are to be removed or reversed; to stop and start the machines when the polishing operation is completed, and to automatically feed the rouge or other polishing medium to the contacting surfaces of the sheet and polishing tools during the polishing operation. Enclosing means are also provided, to protect the workmen from flying rouge and possible broken glass, and also to collect the used rouge and water as thrown from the table.

10 Claims:

1. In an apparatus for polishing plate glass, in combination, a series of polishing tools, and a table having a recess providing a flat sheet-supporting surface, with surrounding tool-supporting surfaces.

2. The combination with a series of polishing tools, of a supporting table for a glass sheet, the table having a recess in its upper face of substantially the same dimensions as the sheet, so that the exposed upper faces of the sheet and table will lie substantially in the same horizontal plane, and the combined upper surfaces of the sheet and table being of sufficient extent to support the polishing tools throughout their paths of movement. 70

3. The combination with a series of polishing tools, of a supporting table for a glass sheet, the table having a recess in its upper face of substantially the same dimensions as the sheet, so that the exposed upper faces of the sheet and table will lie substantially in the same horizontal plane, the exposed face portions of the table which support the polishing members while off from the sheet being formed of a highly polished metal. 80

4. In an apparatus for polishing plate glass, in combination, a series of polishing tools supported on the glass sheet while in operative position, and a supporting table for the sheet, comprising a plane sheet-supporting surface, means to support the polishing tools while off from the edges of the glass sheet, the tool-supporting faces of this means and of the sheet lying in the same plane, and yielding abutments intermediate the means and the sheet edges to limit lateral movement of the sheet on the table. 90

5. In an apparatus for polishing plate glass, in combination, a series of polishing tools supported on the glass sheet while in operative position, and a round sheet-supporting table rotatable about a vertical axis, the table having a shallow polygonal sheet holding recess substantially inscribed within the periphery of the table top, the side portions of the table, around the recess, having their upper surfaces in the same plane as the upper surface of the sheet, to support the polishing tools while off from the edges of the sheet. 100

6. In an apparatus for polishing plate glass, in combination, a series of polishing tools supported on the glass sheet while in operative position, and a sheet-supporting table having a plane master surface for freely supporting the flat ground glass sheet, this surface conforming to but being slightly larger than the sheet to be polished, yielding abutments for limiting lateral movement of the sheet, and supporting means for the polishing tools while off from the edges of the sheet, the tool-supporting surfaces of this means and of the glass sheet lying in substantially the same horizontal plane. 110

7. In an apparatus for polishing plate glass, in combination, a series of polishing tools, supported on the glass sheet while in operative position, and a table having a recess providing a flat sheet-supporting surface, with surrounding tool-supporting surfaces, the tool-supporting surfaces of the ta- 120

130

ble and glass sheet when in position, lying in the same horizontal plane.

8. In an apparatus for polishing plate glass, in combination, a series of polishing tools supported on the glass sheet while in operative position, and a table having a flat sheet-supporting surface, with surrounding tool-supporting surfaces, the tool-supporting surfaces of the table and glass sheet when in position, lying in the same horizontal plane, the tool-supporting portions of the table being vertically adjustable to adapt the apparatus to different thicknesses of plate glass.

15 9. The combination with a series of polishing tools, of a supporting table for the glass sheet, the table having a recess in its upper face of substantially the same dimensions as the sheet, so that the exposed upper faces of the sheet and table will lie substantially in the same horizontal plane and support the tools throughout their paths of movement, and means for vertically adjusting the tool-supporting portions of the table, to adapt the 20 apparatus for polishing different thicknesses 25 of plate glass.

Signed at Toledo, in the county of Lucas and State of Ohio, this 25th day of July, 1923.
